UNITED STATES PATENT OFFICE.

ROBERT B. THURSTON AND CHARLES B. THURSTON, OF BAKERSFIELD, CALIFORNIA.

OIL-WELL PUMP.

Application filed March 18, 1925, Serial No. 16,444. Renewed February 10, 1926.

The present invention aims to provide an oil well pump which is so constituted and operated as to reduce to a minimum the labors expended and the time consumed in 5 installing and removing the pump, which reduces friction to a minimum, which prevents sanding up of the pump, which eliminates the highly undesirable scouring of the plunger by the action of sand under pressure, which costs less to manufacture, install and actuate and which will efficiently 10 pump oil at a greater depth than pumps now in use and which protects the plunger from injury or damage during the introduction 15 of the pump assembly into the well.

Other objects and advantages reside in certain novel features of the construction, arrangement, and combination of parts which will be hereinafter more fully described and particularly pointed out in the appended claims, reference being had to the accompanying drawings forming a part of this specification, and in which:—

Figure 1 is a view partly in section and 20 partly in elevation showing an oil well pump constructed in accordance with the present invention,

Figure 2 is a view in vertical section of the element shown in Figure 1,

Figure 3 is an enlarged fragmentary sectional view showing the manner in which the extension jacket is organized with the working barrel, and

Figure 4 is a view in horizontal section 35 on the line 4—4 of Figure 2.

Referring to the drawings the numeral 1 designates a tubing, to the lower end of which a standing valve barrel or shoe is threaded. The lower end of the shoe 2 carries a pilot nipple 3.

One of the principal features of the present invention is the provision of an oil pumping assembly wherein the plunger is stationary and the working barrel is movable. To this end a standing valve body 4 is fitted in the shoe 2. The upper end of the body 4 is provided with a valve seat 5 with which a ball valve 6 co-acts. The ball valve 6 operates in a cage 7 which has the form of a sleeve and the upward movement of the valve 6 is limited by a cross pin 8. The sleeve 7 is coupled by means of a connection 9 with the lower end of a stationary plunger 10, the plunger 10 being of tubular form and extending vertically up through the tubing 1.

A reciprocable working barrel, designated generally at 11, co-operates with the stationary plunger 10. The working barrel includes a jacket 12 and a liner 13 and at the lower end a lower jacket nut 14 is provided. To the upper end of the jacket and liner a jacket extension 14 is connected by means of an adapter 15. The adapter 15 presents a shoulder 16 within the jacket extension 14, and with this shoulder 16 the flange 17 of a pull nut 18 is designed to coact, the pull nut 18 being threadedly connected with the upper end of the tubular plunger 10.

A connection 20 couples the upper end of the extension jacket 14 with a traveling valve cage 21 in which a ball valve 22 is arranged, the ball valve 22 co-acting with a seat of conventional construction.

As shown in Fig. 3 the liner 13 is held in place in the jacket 12 by the nut 14 and by the adapter 15, the nut 14 and the adapter 15 having ground joints of frusto-conical form with the ends of the liner 13, such joints being designated at 14^a and 15^a, respectively. The proper adjustment having been had in the liner and jacket assembly is maintained by setting or screwing up the lock nut 25 provided on the adapter 15.

In operation, when the sucker rods are reciprocated the working barrel 11 and extension gasket 14 moves up and down and the plunger remains stationary. The weight of the oil and the pressure of the oil holding 90 the valve body 4 down within the shoe 2. On the upstroke of the working barrel oil is drawn in through the valve body 4 and past the valve 6 and fills up the hollow plunger 10 and the jacket extension. Then on the 95 down stroke of the working barrel the oil is expelled upward through the cage 21. In the space between the working barrel and the tubing such a violent agitation is continuously set up that the sand cannot settle 100 during the operation of the pump and when the pump is idle and the working barrel has descended as far as it may this space is practically filled up. As there are no obstructions between the upper and lower valves, 105 and as there is no sand under pressure between the liner and the plunger and as the valve seats may be and are larger than those used in other pumps of the same size the fluid has a greater escapement area and 110 moves more freely and consequently the rods drop free. As there is sufficient clearance

- between the traveling parts and tubing, sand is prevented from packing between the traveling parts and the stationary parts by the action of agitation. There is no scouring of the plunger by sand since sand under pressure may not contact with the plunger. The pump costs less to manufacture, install and operate and will pump oil from a greater depth than is possible for pumps now in use.
- 10 There is a substantial reduction in friction as the plunger does not lift the fluid, such a tight fit as is ordinarily required is not necessary.

Less time is consumed and less labor is expended in installing and removing the pump since the tubing does not have to be removed. All that is necessary to do to remove the pump is to lift up the sucker rod since this action will raise the working barrel and also 20 the plunger, the plunger being lifted by the working barrel by virtue of the engagement of the flange 17 with the shoulder 16. When the plunger is being introduced into the well the plunger 10 is housed and protected in the 25 working barrel and in the extension jacket.

We claim:

1. In an oil well pump, the combination with a tubing having a standing valve shoe, a standing valve body fitted in the shoe, a 20 tubular plunger connected with the standing valve body, the standing valve body being held in line with a reciprocable working barrel co-operable with said plunger and comprised of a jacket and liner or liners, an extension jacket, and an adapter connecting

the extension jacket and the jacket of the working barrel.

2. In an oil well pump, the combination with a tubing having a standing valve shoe, a standing valve body fitted in the shoe, a 40 tubular plunger connected with the standing valve body, the standing valve body being held in line with a reciprocable working barrel co-operable with said plunger and comprising a jacket and liner or liners, an extension jacket, an adapter connecting the extension jacket and the jacket of the working barrel, said adapter providing a shoulder, and a nut engaged with the plunger and co-operable with the shoulder whereby the 50 plunger and standing valve may be lifted from the well when the working barrel is lifted therefrom.

3. In an oil well pump, the combination with a tubing having a standing valve shoe, a 55 standing valve body fitted in the shoe, a tubular plunger connected with the standing valve body, the standing valve body being held in a line with a reciprocable working barrel co-operable with said plunger and comprising a jacket and liner or liners, an extension jacket, an adapter connecting the extension jacket and the jacket of the working barrel, a lock nut co-operable with the 60 lower end of the extension jacket and the working barrel, there being a ground joint between the ends of the liner and the plunger nut and adapter.
